UNITED STATES PATENT OFFICE.

RICHARD BERNHARD, OF MILWAUKEE, WISCONSIN, ASSIGNOR, BY MESNE ASSIGNMENTS, TO WORTHINGTON PUMP AND MACHINERY CORPORATION, A CORPORATION OF VIRGINIA.

DEIER.

1,221,412.

Specification of Letters Patent. Patented Apr. 3, 1917.

Application filed September 5, 1914. Serial No. 860,326.

To all whom it may concern:

Be it known that I, RICHARD BERNHARD, a citizen of the United States, residing at Milwaukee, in the county of Milwaukee and State of Wisconsin, have invented certain new and useful Improvements in Driers, of which the following is a specification, reference being had to the accompanying drawing, forming a part thereof.

10 This invention relates to driers and the objects of the invention are to improve driers in the manner to be hereinafter described and claimed.

Referring to the drawings which accompany this specification and form a part hereof, which drawings illustrate an embodiment of this invention, and on which drawings the same reference characters are used to designate the same parts wherever they may appear in each of the several views, Figure 1 is a vertical, longitudinal section of a drier; Fig. 2 is a vertical, transverse section taken on the line *a—a* on Fig. 1, looking in the direction indicated by the arrows; Fig. 3 is a 20 vertical, transverse section taken on the line *b—b* on Fig. 1, looking in the direction indicated by the arrows; Fig. 4 is an elevation of parts on an enlarged scale; and Fig. 5 is a section taken on the line *5—5* on Fig. 4, 30 looking in the direction indicated by the arrows.

Referring to the drawings, the reference numeral 1 designates a furnace, 2 an inclined, revoluble shell, and 3 an exhaust chamber. The shell 2 is preferably cylindrical and is provided with a gear 4, track ring 5, and a track and a thrust ring 6. The gear 7 meshes with gear 4 to revolve the shell and may be driven in any suitable manner. The 40 track rings 5 and 6 run upon antifriction wheels 8 and 9 and the thrust ring 6 revolves between antifriction, track and thrust wheels 10 and 11. The front end of the shell enters the exhaust chamber 3 through an 45 opening 12 therein and the top 13 of the exhaust chamber is removable so that access can be had to the interior of the chamber. The shell 2 has a flue 14 extending throughout the greater portion of its length but 50 terminating short of both ends of the shell. The reference numeral 15 designates a flue or pipe, preferably made of cast iron, which forms a continuation of flue 14 and which extends beyond the end of shell 2 and out 55 through the side of the exhaust chamber

through an opening 16. The opening 16 is surrounded by a clamp ring 17 made in halves and provided with an internal groove 18 in which is placed a ring 19 which fits freely on flue or pipe 15. The end of the shell 2 within the exhaust chamber 3 is open except for a flange 20 and the flue or pipe 15 is held centrally and removably in position by four adjustable eye bolts 21, only two of which are shown by the drawings. The flue 65 or pipe 15 is slipped over an enlargement 22 of the flue 14 made in the form of a pipe or cylinder. The hot gases and flame are conducted from furnace 1 to the pipe 15 and flue 14 through a fixed flue 23 lined with 70 brick 24. This flue at one end is bolted to a flange casting 25 and its other end is received within the clamp ring 17.

A fan connects with the interior of the exhaust chamber 3 and discharges into the 75 stack 26, being driven by the pulley 27.

A chute 28 extends into the exhaust chamber 3 to discharge the material to be dried into the shell 2 at its front end where the material is forced into the drying chambers 80 of the shell by gravity and the action of the inclined blades or flights 29. The rear end of the shell is closed except for the openings through the discharge spout 30 and buckets 31 are provided for lifting the material so 85 that it will pass out through the discharge spout.

The flue 14 is formed between the convex faces of partitions 32, 33, 34 and 35 which extend longitudinally within the shell 2 and which, in cross section, have the general shape of arcs of circles. Each of these partitions is fastened at one edge to the shell 2 and at its other edge to the convex side of the next adjacent partition, as clearly shown 95 by Fig. 3 of the drawings. As these partitions are exposed to a higher temperature than the shell 2, their form allows them to expand and contract under the influence of changes of temperature without injuriously 100 affecting the shell. In order to provide for the longitudinal expansion and contraction of the partitions 32, 33, 34 and 35 they are made in several lengths with the ends of the 105 lengths in alignment but separated sufficiently to allow for the expansion and the joints between the lengths are made practically tight by butt straps 36 which are secured in any suitable manner, by rivets for example, to one length only and extend over 110

the joint onto the next adjacent length. The several lengths of the partitions are secured to the shell 2 by bolts which extend through bolt holes in the shell and elongated, or 5 slotted, bolt holes in the partitions which allow for the longitudinal expansion of the several lengths of the partitions.

The partitions 32, 33, 34 and 35 form drying chambers 37, 38, 39 and 40 within the 10 shell 2 for the material to be dried and lifters 41 are provided in the drying chambers to prevent the material remaining in one mass at the bottoms of the drying chambers.

15 The operation of the apparatus is as follows: The flame and hot gases from the furnace 1 pass through flue 23, flue or pipe 15, and flue 14 heating the partitions 32, 33, 34 and 35. The gases will have cooled below 20 the ignition temperature before reaching the end of flue 14 even if the combustible gases have not been entirely consumed. The fan draws the gases back through the drying chambers 37, 38, 39 and 40, drying the 25 material therein, and the gases pass into the exhaust chamber 3 and out through the stack 26. Air enters the drying chambers through the discharge spout 30 and mixes with the gases from flue 14. Material to be 30 dried is fed through chute 28 into the end of the shell 2 and by gravity and the inclined blades or flights 29 is crowded into the drying chambers. Owing to the inclination of the shell 2, the material works along 35 the shell, as it revolves, until it falls from the drying chambers at the end of shell 2 where it is picked up by the buckets and discharged through the discharge spout 30. The shell 2 is revolved in the direction indicated by the arrow on Fig. 3 of the drawings and it will be noticed from an inspection of Fig. 3 that during a part of a revolution of shell 2 the material to be dried 40 will lie upon a highly heated partition and will be heated to drive the moisture therefrom. The hot gases passing through the drying chambers will absorb the moisture and tend to maintain the heated condition of the material and the air which enters 45 through the discharge spout 30 and mixes with the hot gases increases the total volume of gases and, consequently, their moisture absorbing capacity.

50 What is claimed is:

55 1. The combination with a revoluble shell

of a plurality of transversely curved partitions connected with the shell and with each other to form a flue and drying chambers.

2. The combination with a revoluble shell 60 of a plurality of transversely curved partitions connected with the shell and with each other to form a flue and drying chambers, each of said partitions being composed of sections with the ends of the sections forming such partition approximately in line 65 with each other, and butt straps extending over the joints between adjacent sections and secured to one of said sections.

3. The combination with a revoluble shell 70 of a plurality of transversely curved partitions movably secured to the shell and secured to each other to form a flue and drying chambers, each of said partitions being composed of sections with their ends approximately in line with each other, and 75 butt straps extending over the joints between the sections and secured to one of the sections.

4. The combination with a revoluble shell 80 of a plurality of transversely curved partitions composed of sections, each section being movably secured to the shell and secured to another section to form a flue and drying chambers, and means to close the joint between the ends of sections forming a partition 85 while permitting relative movements between said ends.

5. The combination with a revoluble shell 90 provided with partitions extending for a part of the length thereof to form a flue and drying chambers, of a pipe secured to 95 said shell and communicating with said flue.

6. The combination with a revoluble shell 100 provided with partitions extending for a part of the length thereof to form a flue and drying chambers, of an exhaust chamber into which one end of the shell extends, a pipe secured to said shell, communicating with said flue and extending out through an opening in said exhaust chamber, a grooved clamp ring secured to the exhaust chamber, and a ring on said pipe engaged with said clamp ring.

In witness whereof I hereto affix my signature in presence of two witnesses.

RICHARD BERNHARD.
